UNITED STATES PATENT OFFICE.

ARTHUR HENRY GLEDHILL, OF HALIFAX, ENGLAND.

WORKMAN'S TIME RECORDER.

Application filed November 17, 1926, Serial No. 148,900, and in Great Britain November 14, 1925.

This invention relates to workmen's time recorders of the type in which a portion of the card is removed at each stamping operation and has for its chief object to introduce an improved form of mechanism for preventing the machine from being operated until a card has been placed in its correct position in the card sheath or card holder. For this purpose it has been proposed to introduce mechanism for arresting the movement of the main operating handle or preventing the printing hammer striking the card and to utilize the card by pressing on it to actuate lever mechanism to release the main operating handle or the printing hammer. This pressure upon the card is objectionable for the following reason. To get a clean cut card it is necessary that the card should accurately fit the card sheath but in the commercial supply of time cards a slight variation will occur in the width. This produces a sufficient amount of play to enable the card to move about in the holder and cause a jagged edge to be cut. To overcome this objection the clipper plunger or cutter is in some cases formed with a wedge shaped portion which presses the card to one side of the sheath and aligns it always from one face during the cutting operation, with the result that a clean cut card is produced. When however, it is necessary to press upon the card to cause it to release arresting or locking mechanism this pressure overcomes the pressure that is exerted upon it by the wedge and renders the cutting operation irregular; moreover, in the case of damp or soft cards it is easy for the card to fail to operate the releasing mechanism, and if further pressure is applied to the card, it forces the latter down to such an extent that the card can be finally clipped in an upper intermediate portion and be stamped in the wrong place.

According to this invention until a card has been placed in its correct position in the card sheath or card holder, an arresting device moving with the clipper plunger or cutter occupies a position to prevent the main operating handle, or the printing hammer from functioning and is moved out of its arresting position by a feeler coming in contact with the face of the card when the latter is in its correct position in the card sheath or card holder.

In order that the said invention may be clearly understood and readily carried into effect, the same is described more fully with reference to the accompanying drawings, in which:

Fig. 1 is an elevation of the cutter unit 60 provided with an arresting device in accordance with this invention.

Fig. 2 is a plan of the apparatus shown in Fig. 1.

Fig. 3 is a similar view to Fig. 1 showing 65 the arresting device moved to its inoperative position by the action of a card.

Fig. 4 is a front elevation of the plunger or cutter drawn to a larger scale, and Fig. 5 is a perspective view of a portion of the 70 cutter.

Fig. 6 is a section and Fig. 7 a front view showing the nature and action of the mechanism connecting the arresting device to the main operating lever.

A indicates the card, B the cutter, C the arresting device, D the feeler, E the main operating handle, and F the printing hammer.

In the example shown the arresting device 80 C comprises a plate which is pivotally mounted on the clipper plunger b or on a part that moves therewith. This plate is formed with a detent c and actuated by gravity or through the intervention of a 85 spring to cause such detent normally to occupy a position in which it will engage a stop c¹ to prevent the operating handle E or printing hammer F from functioning. The handle E is connected with the clipper plunger b by a link e attached to an arm e¹ that is rigidly fixed on a shaft e². Rigidly fixed on such shaft are two arms e³ and between such arms is a roller e⁴ rotatably mounted on a rod e⁵ that is carried by the 90 arms. The roller e⁴ engages a hook b¹ on the clipper plunger b and forces the plunger in to perform the clipping operation when the main operating handle is depressed at the termination of which movement the 100 parts are returned to their normal position by a spring e⁶.

If desired, to prevent the printing hammer F from functioning except when the card is placed in its correct position in the card sheath or card holder an intercepting device may occupy a position between the printing hammer or some part that moves therewith and a stop or buffer and be moved out of such position by the insertion of a card to allow the printing hammer to print. The stop c¹ may be fixed to or form part of a stationary part of the 105 110 115

cutter unit or other suitable part of the machine and be formed with ratchet teeth for engagement with the detent *c*. The feeler *D* comprises an abutment projecting from a card support *a* which is slidably mounted in a passage *b*¹ formed longitudinally along the clipper plunger *b*. Projecting from the rear end of the card support is an arm *a*¹ that is engaged by an inclined or cam surface *c*² on the pivoted plate *C*. With this construction unless a card is resting on the card support, the arm thereon moves with the clipper plunger through the action of a spring *b*² during the initial movement of the plunger and maintains the pivoted plate *C* in a position to engage the stop *c*¹ and prevent the operating handle *E*, or printing hammer *F* from functioning. If a card is resting on the card support as shown in Fig. 3, the feeler *D* comes in contact with the card face during the initial movement of the operating handle and clipper plunger. When this takes place the sliding movement of the card support is arrested and the continued movement of the clipper plunger causes the inclined or cam surface on the pivoted plate to travel over the arm *a*¹ on the card support and move the detent to a position in which it will clear the stop *c*¹ and allow the operating handle *E*, or printing hammer *F* to function.

What I claim as my invention and desire to secure by Letters Patent in the United States is:—

1. In a time recorder of the character described, operating mechanism for operating on an inserted card including a member movable toward and away from the card, and arresting means normally preventing the functioning of said mechanism and including a feeler movable with and relatively to said member and adapted to contact with and be stopped by said card when the card is in proper position and thereby render the arresting means ineffective when said member is moved toward the card.

2. In a time recorder of the character described, operating mechanism for operating on an inserted card including a member movable toward and away from the card, an arresting member mounted movably on the firstnamed member, a stop in the path

of said arresting member to normally prevent the functioning of said mechanism, and a feeler movable with and relatively to the firstnamed member and adapted to contact with and be stopped by the card when the card is in proper position and controlling said arresting member whereby the movement of the firstnamed member toward the card with the feeler stopped by the card will move said arresting member to a position to avoid said stop.

3. In a time recorder of the character described, operating mechanism for operating on an inserted card including a plunger movable toward and away from the card, an arresting member mounted movably on the plunger, a stop in the path of said arresting member to normally prevent the complete movement of the operating mechanism when the plunger is moved toward the card, and a feeler mounted for sliding movement on the plunger and moved yielding with the plunger toward the card, said feeler being adapted to contact with and be stopped by the card when the card is in proper position, and said arresting member being controlled by the feeler to move the arresting member to a position to avoid said stop when said plunger is moved toward the card with the feeler stopped by said card.

4. In a time recorder of the character described, operating mechanism for operating on an inserted card including a plunger movable toward and away from the card, an arresting member pivoted to said plunger and having a detent and a cam, a stop in the path of said detent for normally preventing the functioning of said mechanism, and a feeler slidably on the plunger and yielding moved with the plunger toward the card, said feeler being arranged to contact with and be stopped by the card when the card is in proper position, and the feeler having a portion to engage said cam and swing the arresting member to move the detent to a position to avoid said stop when the plunger is moved toward the card with said feeler stopped by said card.

In testimony whereof I affix my signature.

ARTHUR HENRY GLEDHILL.
